UNITED STATES PATENT OFFICE.

THOMAS SILK, OF PORTSMOUTH, OHIO.

SHEET-METAL BARREL.

1,225,876.

Specification of Letters Patent. Patented May 15, 1917.

Application filed July 8, 1916. Serial No. 108,083.

To all whom it may concern:

Be it known that I, THOMAS SILK, a citizen of the United States of America, and resident of Portsmouth, county of Scioto, 5 and State of Ohio, have invented certain new and useful Improvements in Sheet-Metal Barrels, of which the following is a specification.

This invention relates broadly to sheet-metal barrels, and more particularly to a chime for such barrels.

The primary object of the invention is to provide a steel barrel wherein the body and head are relatively disposed to form a chime 15 and wherein said parts have their extreme edges united by welding.

A further object is to provide in association with a welded-seam chime and a chime-embracing hoop, means whereby said hoop 20 is effectually interlocked with said chime.

A still further object of the invention is to provide, in association with a chime and a reinforcing chime-hoop, a wire ring which constitutes a locking medium between said 25 chime and said hoop.

With these and other objects in view, the invention resides in the features of construction, arrangement of parts and combinations of elements which will hereinafter be 30 exemplified, reference being had to the accompanying drawings, forming a part of this specification, in which—

Figure 1 is a vertical section of one end of a barrel constructed in accordance with 35 my invention, and—

Fig. 2 is a detail section illustrating a modified form.

Referring specifically to Fig. 1, which illustrates the preferred form of invention, 40 1 indicates the body of a sheet-metal barrel, and 2 a head of said barrel. Said head, which has a peripheral flange 3, is disposed in seated position within the end of said body with said flange closely engaging the 45 latter, the edge of said flange and the edge of said body being flush, one with the other, after which said edges are welded together in any appropriate manner to a depth approximating the thickness of the metal.

50 A wire ring 4 is disposed in embracing relation to the chime constituted by the engaging portions of the body 1 and head-flange 3 at a suitable distance below the welded edges of said parts; and disposed in 55 embracing relation to said chime and said ring is a relatively heavy metal hoop 5 hav-

ing the inner member 6 thereof disposed in substantially vertical position in close-fitting relation to the flange 3 and having the outer member 7 thereof bent downward about and clenched under said ring 4.

In applying the hoop 5, a great pressure is applied for rolling or turning the member 7 into interlocking relation with the ring 4. This pressure suffices to force the ring 4 65 slightly inward, indenting or forming a perceptible bow in the chime, as shown at 8. This bow may also extend to the inner member 6 of the hoop, as shown at 9. Being received in the seat constituted by the indentation of the metal, as aforesaid, said wire ring 4 obviously serves as a medium whereby chance disengagement of the hoop from the chime is prevented. In other words, since the ring is maintained by the 75 hoop in positive seating relation to the chime, and said hoop is disposed in clamping relation to said ring, the hoop and chime are positively interlocked.

In the modification shown in Fig. 2 the 80 body 1^a and head flange 3^a have their edges bent upon each other to form an interlocked seam as distinguished from the welded seam in Fig. 1, and the wire ring 4^a is disposed in closely underlying relation to said interlocked seam. The metal hoop 5^a is disposed in interlocking relation to said ring substantially as in Fig. 1.

What is claimed is—

1. A sheet-metal barrel comprising a 90 body, a head having a peripheral flange, said flange being seated within an end of said body to form a chime of double thickness, a wire ring embracing said chime, and a chime-embracing hoop having a part disposed in seated relation to the inner face of said chime and having another part bent to conformably embrace and interlock with said ring.

2. A sheet-metal barrel comprising a 100 body, a head having a peripheral flange, said flange being seated within an end of said body to form a chime of double thickness, said chime being slightly bowed to form an annular channel, a wire ring seated 105 in said channel, and a hoop having a part disposed in close-fitting relation to the inner face of said chime and having another part bent to embrace and interlock with said ring.

3. A sheet-metal barrel comprising a 110 body, a head having a peripheral flange,

said flange being seated within an end of said body to form a chime of double thickness, said chime being slightly bowed to form an annular channel, a wire ring seated in said channel, and a hoop disposed in inclosing relation to the chime and said wire and interlocking with the latter.

4. A sheet-metal barrel comprising a body, a head having a peripheral flange, 10 said flange being seated within an end of said body to form a chime of double thickness, the parts of said chime having their edges welded together, a ring embracing said chime, and a hoop disposed in clamping relation to said chime and said ring, 15 said hoop being interlocked with said ring and exerting such a binding force that a ring-seating indentation is formed in said chime.

20 5. A sheet-metal barrel comprising a body, a head having a peripheral flange, said flange being seated within an end of said body to form a chime of double thickness, the parts of said chime having their

edges welded together, a ring embracing 25 said chime, and a hoop disposed in inclosing relation to said chime and said ring, said ring being interlocked with said chime and said hoop being interlocked with said ring.

6. A sheet-metal barrel comprising a body, a head having a peripheral flange, 30 said flange being seated within an end of said body to form a chime of double thickness, the parts of said chime having their 35 edges welded together, a hoop disposed in inclosing relation to said chime, and a member interposed between said hoop and one side of said chime constituting a locking medium whereby the former is interlocked 40 with the latter.

In testimony whereof, I affix my signature in presence of two subscribing witnesses.

THOMAS SILK.
